PERFORATOR

Chester I. Wagner, Brooklyn, N. Y., assignor to
Safety Fastener Co., Bloomfield, N. J., a corporation of New Jersey

Application October 20, 1938, Serial No. 235,999

11 Claims. (Cl. 164—120)

This invention relates to a perforator and has special reference to a device for perforating sheets to provide binding holes or the like at predetermined spaced distances from each other and from the binding edges and centers of the sheets.

More particularly, this invention relates to a perforator comprising a single piece of spring metal bent to form opposed spaced arms with a male die member on one of the arms for registration and co-operation with an aperture in the other of the arms to perforate a sheet interposed therebetween, there being means on the piece for gauging the location of the perforation simultaneously laterally and longitudinally of the sheet.

In order to bind sheets into covers, folders, file drawers and the like, it is desirable to provide binding holes in the sheets and such binding holes necessitate accuracy in placement thereof on the sheets so that the edges of the sheets are in alignment. The sheets are bound ordinarily by paper fasteners and the two-prong type is in common use. For convenience in manufacture, the prongs of the paper fasteners are spaced apart predetermined standard distances.

In perforating sheets to be received by paper fasteners of the above type it is desirable that each sheet to be perforated have the perforations gauged the standard distances between prongs of the paper fasteners and also to gauge the perforations a standard distance from the binding edge of the sheet. Obviously, it is desirable that the binding holes be spaced equi-distantly or at a fixed distance from the center of the binding edge of the sheet. Perforators now in common use employ two punch heads separated by a fixed spacing with the perforations being related to the edge and center of the binding edge of the sheet by separable adjustable means. Perforators of this type are comparatively expensive and are likewise cumbersome. Types of perforators having a single die member of which applicant has knowledge gauge distances between perforations separately and require adjustment before use, with the perforating being done one hole at a time.

It is one object of this invention to provide a perforator of the type indicated above which is simple in operation, is comparatively inexpensive to manufacture, is of small size, and is durable.

It is another object of this invention to provide a perforator of the character indicated above in which perforations may be accurately spaced and centered in three directions, that is, uniformly spaced between holes, uniformly spaced from

the binding edge of the sheet, and equi-distantly spaced from the center of the sheet.

It is a further object of this invention to provide a perforator of the type hereinabove noted which is capable of gauging more than one standard spacing between holes without requiring mechanical adjustment.

Other objects and advantages of this invention will hereinafter be more particularly pointed out and for a more complete understanding of the characteristic features of this invention, reference may now be had to the following description when taken together with the accompanying drawing, in which latter:

Figure 1 is an elevational view in plan of the 15 perforator embodying the features of this invention, the perforator being shown in position prior to the final bending operation to form opposed arms;

Fig. 2 is an enlarged central longitudinal sectional view of the perforator of Fig. 1 in a completed state;

Fig. 3 is a plan elevational view of the perforator of Fig. 2, showing the position thereof with respect to a sheet to be perforated;

Fig. 4 is a plan elevational view of a fragmentary portion of the perforator of Fig. 2, showing its position with respect to another sheet to be perforated; and

Fig. 5 is a plan view of a fragmental portion of 30 a perforated sheet showing its relation to a fastener base.

Referring now more particularly to the drawing, the perforator 10 is shown as comprising a single piece of spring metal bent to form opposed 35 spaced arms 11 and 12. Annular embossments 13 and 14 are formed in the arms 11 and 12 respectively adjacent the free ends of the arms with longitudinal embossments 15 and 16 extending from the annular embossments over a major portion 40 of the length of the arms.

The material 17 between the annular embossment 13 is formed into a substantial conical shape having a central aperture 18. The material 19 between the annular embossment 14 is likewise 45 formed into a substantial conical shape with an axial portion thereof being formed into a tubular projecting portion 20 having a V-shaped crotch 21 in the outer end thereof. The tubular projection 20 co-operates with the aperture 18 to 50 perforate a sheet interposed therebetween and between the arms 11 and 12.

Each of the arms is provided with an offset portion 22 extending in a direction from the free end portions of the arms toward each other to 55

provide fulcrums at the junctures of the free end and offset portions for the flexing of the arms. The offset portions 22 thus formed effect a permanent set of the arms relative to the plane of flexure thereof so that the projection 28 and the aperture 18 are in axial alignment, the offset portions being preferably formed while the projection and aperture are held in an axially aligned position.

- 10 A projection 23 is preferably cut and deformed from the material of the arm 11 to extend in the direction of the arm 12 to act as a gauge to locate a perforation or perforations to be made in the sheet. It may be desirable to have 15 the free end of the projection terminate closely adjacent to the arm 12 for substantially limiting the flexing movement of the arms to the free end portions thereof extending in a plane beyond the projection 23. A second projection 24 is likewise cut and deformed from the material preferably of the arm 11 to extend in the direction of the other arm 12, the projection being preferably of L-shape and extending to a point midway of the normal spacing between 25 the arms. The projection 24 acts as a gauge to determine the location of a perforation or of perforations to be made in the sheet, the projections 23 and 24 being selectively employed for gauging the locations of the perforations.
- 30 A flange 25 is preferably formed integrally with and extends longitudinally along one side of the arm 11 and in the direction of the arm 12 terminating preferably slightly short of the L-shaped projection 24. The flange 25 also acts to 35 predetermine the location of a perforation or perforations to be cut in the sheet.

In the operation of the perforator above described, to perforate a sheet with the widest spacing between perforations, the sheet is doubled 40 with matched edges and pinched together at the fold to locate the center thereof, the condition of the sheet being shown in dotted lines in Figure 2 and the folded sheet being indicated by the numeral 26. The folded sheet 26 is inserted 45 between the arms 11 and 12 of the perforator, fold first, with the binding edge against the flange 25, the sheet being carried under and past the projection 24 with the edge of the folded central portion engaging the projection 23. The 50 arms 11 and 12 are flexed in a direction toward each other by a pressing engagement, the male die member 20 co-operating with the aperture 18 to perforate the sheet.

Referring now to Figure 5 of the drawing, 55 when the sheet is removed from the perforator and unfolded, the perforations are equi-distantly spaced from the center fold of the sheet, the fold being indicated by the dot and dash line A—A, and are spaced a standard distance as indicated by the dot and dash line B—B from the binding edge of the sheet as determined by the flange 25. The spacing of the perforations is standard to the distance between two prongs C of one standard paper fastener base D. The 60 perforations are thus simultaneously gauged laterally and longitudinally of the sheet, equi-distantly from the center thereof.

In the operation of the perforator to accommodate the spacing between prongs of a second 70 standard paper fastener of lesser distance between the prongs, the folded sheet 26a is disposed between the arms 11 and 12 of the perforator with the edge of the folded central portion resting against the perpendicularly extending portion of the projection 24. The binding

edge of the sheet is rested against the flange 25 in order to predetermine the spaced relation of the perforation from the edge thereof.

The position of the sheet 26a in the perforator is shown more particularly in Figure 3, the binding edge resting against the flange 25 and the edge of the folded central portion resting against the upright portion of the projection 24. A movement of the arms in a direction toward each other permits a co-operation of the male 10 die member 20 with the aperture 18 to perforate the sheet. When the sheet 26a is removed and unfolded a uniform spacing from the center of the sheet as well as between holes and from the binding edge of the sheet is obtained. The only 15 difference between the operation just described and the perforating operation previously described is in the smaller spacing between the holes.

It is not essential in some instances to preserve 20 the spacing from the binding edge and by reference to Figure 2 it will be noted that the flange 25 does not extend as deeply as the L-shaped projection 24 and thus the binding edge of sheet 26a, instead of abutting against the flange 25, 25 may extend under and beyond the flange 25 to rest on the ledge provided by the L-shaped projection 24. The same condition may result with respect to the sheet 26 which may not be bent up to engage the flange 25 but may extend under 30 and beyond the flange 25 as well as the projection 24.

The end of the flange 25 may also determine a fixed spacing for a sheet 26b either singly or folded where it is desired to have a smaller spacing between the holes or to provide a predetermined spacing between the perforation and the edge of the sheet. 35

Referring now more particularly to Figure 4 of the drawing, the perforator may be employed 40 to make single perforations where the desired distance from the binding edge of the sheet is standard but the spacing between holes is not standard. In this instance perforation locations are determined by laying out and marking the 45 locations 27, whereafter the sheet is inserted between the arms 11 and 12 with the binding edge resting against the end of the flange 25 of the perforator with the marked locations being centered and viewed through the opening 18. 50

While but a single embodiment of this invention is herein shown and described, it is to be understood that various modifications thereof may be apparent to those skilled in the art without departing from the spirit and scope of this 55 invention and, therefore, the same is only to be limited by the scope of the prior art and the appended claims.

I claim:

1. A perforator comprising a single piece of 60 spring metal bent to form opposed spaced arms, each of said arms having a free end portion with an offset portion extending in a direction toward each other providing fulcrums at the junctures of the free end and offset portions for the flexing of said arms, a male die member on one of said arms for registration and co-operation with an aperture in the other of said arms to perforate a sheet interposed therebetween, and means on said piece for gauging the location of 65 70 said perforation.

2. A perforator comprising a single piece of spring metal bent to form opposed spaced arms, at least one of said arms having a free end portion with an offset portion extending in a direc- 75

tion toward the other of said arms to provide a fulcrum at the juncture of the offset and free end portions for the flexing of said arm, a male die member on one of said arms for registration and co-operation with an aperture in the other of said arms to perforate a sheet interposed therebetween, and a projection on one of said arms extending adjacent said offset portion in the direction of the other of said arms for gauging the location of said perforation.

3. A perforator comprising a single piece of spring metal bent to form opposed spaced arms, each of said arms having a free end portion with an offset portion extending in a direction toward each other providing fulcrums at the junctures thereof for the flexing of said arms, a male die member on one of said arms for registration and co-operation with an aperture in the other of said arms to perforate a sheet interposed therebetween, and a projection on one of said arms adjacent the offset portion thereof and extending in the direction of the other of said arms for gauging the location of said perforation.

4. A perforator comprising a single piece of spring metal bent to form opposed spaced arms, an annular embossment in each of said arms adjacent the free ends thereof extending in a direction away from each other and the material within said embossments being substantially conical-shaped in cross section and extending in a direction toward each other, a male die member on one of said conical-shaped portions for registration and co-operation with an aperture in the other of said conical-shaped portions to perforate a sheet interposed therebetween, and means on said piece for gauging the location of said perforation.

5. A perforator comprising a single piece of spring metal bent to form opposed spaced arms, an annular embossment in each of said arms adjacent the free ends thereof with longitudinal embossments extending therefrom over a major portion of the length of the arms, the material within the annular embossments being substantially conical-shaped in cross section and extending in a direction toward each other, a male die member on one of said conical-shaped portions for registration and co-operation with an aperture in the other of said conical-shaped portions to perforate a sheet interposed therebetween, and means on said piece for gauging the location of said perforation.

6. A perforator comprising a single piece of spring metal bent to form opposed spaced arms, a male die member on one of said arms for registration and co-operation with an aperture in the other of said arms to perforate a sheet interposed therebetween, a flange formed integrally with and extending longitudinally along one side of one of said arms and in the direction of the other of said arms for engaging one edge of the sheet, and a plurality of spaced projections formed integrally with and intermediate the width of one of said arms and extending in the direction of the other of said arms for selectively engaging another edge of the sheet.

7. A perforator comprising a single piece of spring metal bent to form opposed spaced arms, a male die member on one of said arms for registration and co-operation with an aperture in the other of said arms to perforate a sheet interposed therebetween, a flange extending longitudinally along one side of one of said arms and in the direction of the other of said arms for engag-

ing one edge of the sheet, and a plurality of spaced projections intermediate the width of one of said arms and extending in the direction of the other of said arms for selectively engaging another edge of the sheet, said projections being of unequal lengths and at least one of said projections being of L-shaped configuration.

8. A perforator comprising a single piece of spring metal bent to form opposed spaced arms, a male die member having a tubular projecting portion formed integrally on one of said arms for registration and co-operation with an aperture in the other of said arms to perforate a sheet interposed therebetween, a flange extending longitudinally along one side of one of said arms and in the direction of the other of said arms, one edge of the sheet selectively engaging the end of said flange or the side wall of said flange for gauging the location of said perforation.

9. A perforator comprising a single piece of spring metal bent to form opposed spaced arms, a male die member having a tubular projecting portion formed integrally on one of said arms for registration and co-operation with an aperture in the other of said arms to perforate a sheet interposed therebetween, said tubular projecting portion having a V-shaped crotch in the outer end thereof, a flange extending longitudinally along one side of one of said arms and in the direction of the other of said arms for engaging one edge of the sheet, and a plurality of spaced projections intermediate the width of one of said arms and extending in the direction of the other of said arms for selectively engaging another edge of the sheet.

10. A perforator comprising a single piece of spring metal bent to form opposed spaced arms, a male die member having a tubular projecting portion formed integrally on one of said arms adjacent the free end thereof for registration and co-operation with an aperture in the other of said arms adjacent the free end thereof to perforate a sheet interposed therebetween, said tubular projecting portion having a V-shaped crotch in the outer end thereof, a flange extending longitudinally along one side of one of said arms and in the direction of the other of said arms for engaging one edge of the sheet, and a plurality of spaced projections intermediate the width of one of said arms and extending in the direction of the other of said arms for selectively engaging another edge of the sheet, one of said projections being disposed adjacent the bent ends of said arms for substantially limiting the flexing movement to the free ends thereof.

11. A perforator comprising a single piece of spring metal bent to form opposed spaced arms, a male die member for registration and co-operation with an aperture adjacent the free end of the other of said arms to perforate simultaneously both portions of a centrally folded sheet interposed therebetween, a flange extending longitudinally along one side of one of said arms and in the direction of the other of said arms for engaging a binding edge of the sheet, a projection on one of said arms intermediate the width thereof and extending in the direction of the other of said arms for engaging the edge of the folded central portion of the sheet whereby perforations are gauged laterally and longitudinally of the sheet and equi-distantly from the center thereof.

CHESTER I. WAGNER.
